UNITED STATES PATENT OFFICE.

OGDEN P. LETCHWORTH, OF BUFFALO, NEW YORK.

HAME ATTACHMENT.

SPECIFICATION forming part of Letters Patent No. 296,193, dated April 1, 1884.

Application filed October 30, 1883. (No model.)

To all whom it may concern:

Be it known that I, OGDEN P. LETCHWORTH, of the city of Buffalo, in the county of Erie and State of New York, have invented a new 5 and useful Improvement in Hames, of which the following is a specification.

This invention relates to an improvement in the construction of the hame-staple to which the hame-tug is attached, and has for its object to avoid the weakening of the body of the 10 hame by the two holes which are ordinarily formed through the body of the hame for the reception of the two legs of the hame-staple.

My invention consists, to that end, of a hame 15 staple or loop secured to the body of the hame by a single bolt or rivet, as will be hereinafter fully set forth, and pointed out in the claims.

In the accompanying drawings, Figure 1 is a front elevation of a portion of a hame provided with my improvements. Fig. 2 is a side elevation of the same. Fig. 3 is a horizontal section in line *x x*, Fig. 1.

Like letters of reference refer to like parts in the several figures.

25 A represents the hame; B, the hame staple or loop, and C the hook to which the breast-strap ring D is attached.

F represents a clasp plate or frame, which extends from the base of the staple B around 30 the front portion of the hame, and G represents the bolt or rivet whereby the staple is secured to the hame. The clasp or frame F is cast in one piece with the staple or loop B, and provided between the legs of the staple or 35 loop with an opening, *f*, and the inner side of the hame is provided with a similar countersunk opening, *f'*. The rivet G is passed through the openings *f f'* of the frame F, and through an opening formed in the hame A 40 and the metallic hame-strap *a*, and riveted over at one end, whereby the frame F and

hame staple or loop B, cast on the same, are firmly secured to the hame A. The hook C is cast on the frame F, and rests with its open end against the front side of the hame 45 A, whereby the jaw of the hook is closed after the frame has been applied to the hame and the breast-strap ring D confined in the hook C.

It will be seen from the foregoing that the 50 staple or loop is secured to the hame by a single bolt or rivet, thereby avoiding the formation of two bolt-holes through the body of the hame at the point where the draft is applied to the hame, and where the greatest strength is required. The frame F extends around the 55 front side of the hame in line with the opening formed through the same, and compensates for the reduction in strength of the hame-body, caused by the formation of the bolt-hole through the same, and forms a very secure 60 fastening for the hame staple or loop and materially increases the strength of the hame at this point.

I claim as my invention—

1. The combination, with a hame, of a hame 65 staple or loop, a frame or clasp extending from the base of the hame staple or loop to the opposite side of the hame, and a bolt or rivet whereby said frame and staple or loop are secured to the hame, substantially as set forth. 70

2. The combination, with a hame, of a hame staple or loop, a frame or clasp extending from the base of the staple or loop to the opposite side of the hame, a hook adapted to receive the breast-strap ring, and cast on said 75 clasp or frame, and a bolt or rivet whereby said clasp and staple or loop are secured to the hame, substantially as set forth.

O. P. LETCHWORTH.
